UNITED STATES PATENT OFFICE.

MARK STAVELEY HOBAN, OF LONDON, ENGLAND.

CIRCUIT BREAKER.

Application filed September 20, 1926, Serial No. 136,484, and in Great Britain October 12, 1925.

This invention relates to a circuit breaker or switch for use in electric circuits and which may be hand operated or arranged to operate automatically on the passage of an excess current.

One form of circuit breaker according to the invention and for use in a distribution board for an electrical installation in place of the usual fusible cut out will be described with reference to the accompanying drawings wherein:—

Fig. 1 shows the circuit breaker with the cover and actuating lever removed;

Fig. 2 shows the member of insulating material;

Fig. 3 is a plan of the operating mechanism; and

Fig. 4 an elevation of the circuit breaker with the cover in position.

1 is a body part of insulating material which is recessed at 2 and has contact blades 3, 4 similar to those of an ordinary fuse block, one mounted at each end. To the blade 3 is connected a conducting strip 5 which extends into the recess 2, and to the blade 4 a conducting strip 6 which extends over the recess 2. A V-shaped bi-metallic strip is disposed in the recess 2 and is secured at the end of one arm 7 to the end of the 25 conducting strip 5 and to the body part 1. The end of the other arm 8 is secured to one end of a conducting strip 9 also in the recess 2 and to the body part 1. The conducting strip 9 is so disposed that its other end lies 30 under the end of the conducting strip 6. On a pin 10 extending from the body part 1 and in the recess 2 is rotatably mounted a sector-shaped member of insulating material 35 11. Towards one corner the member 11 carries a stud 12 of conducting material, the position being such that at one end of the movement of the member 11 the said stud is disposed between and engages the conducting strips 6 and 9 to complete an electrical connection between the two. A flat spring arm 40 13 is rotatably mounted at one end on the pin 10 and extends along one edge of the member 11. Towards its other end it carries a pin 14 which projects through a hole in 45 the member 11 and engages a stop 15 carried on an actuating lever 16 which is pivotally mounted on the pin 10 without the cover 19 for the body part 1 (see Fig. 4). A spring 50 17, which is connected at one end to the member 11 and is anchored at the other end to a stationary part of the circuit breaker, acts

to urge the member 11 in a clockwise direction. The base 18 of the V-shaped bi-metallic strip 7, 8 is bent over to embrace the end of the spring arm 13.

60 The bi-metallic strip is of well known form consisting of strips of different metals such as brass and steel brazed or otherwise joined throughout their length so that when heated the strip bends, due to the different coefficients of expansion of the two metals.

65 When the circuit breaker is connected in an electrical circuit and the parts are in the position shown in Fig. 1, current flows from the contact 3 through the conducting strip 70 5, the bi-metallic strip 7, 8, the conducting strips 9 and 6 to the contact 4. Should the current exceed a predetermined value, the bi-metallic strip will heat and bend towards the body part 1, whereby the bent base 18 75 will engage the end of the spring arm 13 and withdraw the pin 14 from engagement with the stop 15. The member 11 is then free to rotate in a clockwise direction under the action of the spring 17, whereby the circuit is rapidly broken and an arc is prevented by the insertion of the member 11 between the conducting strips 9 and 6.

75 The circuit breaker is replaced or the circuit remade by rotating the operating lever 80 16 first in a clockwise direction until the pin 14 again comes under the stop 15, and then in an anti-clockwise direction so that the position shown in Fig. 1 is restored. If the abnormal conditions in the electric circuit are still maintained, the bi-metallic strip will be immediately heated and the circuit broken, even though the operating lever 16 be held in position.

85 The construction of the parts is such as 90 to limit the travel of the operating lever 16 and of the member 11.

95 It will be understood that various modifications may be made in the form of the invention illustrated in the drawings. Thus 100 the insulating material 11 may be mounted to move in a straight line and may be of other than sector shape. It may be necessary to deal with currents which are much larger or much smaller than those normally 105 used in electric lighting circuits, in which case a portion only of the total current will be passed through the bi-metallic strip or the strip will be heated by passing the current through a separate heating element. 110 Similarly the movement of the piece of insulating material may be brought about by

electromagnetic means either to close or to open the circuit.

For use as a switch means may be provided to release mechanically the catch constituted by the pin 14 engaging the stop 15.

What I claim is:—

1. A circuit breaker for an electric circuit comprising a pair of contacts, a member of insulating material carrying a conducting stud and movable in relation to said contacts to bring the stud into engagement therewith or to move it therefrom, spring means to move said member, a detent to hold up said movement, and a V-shaped bi-metallic strip member electrically connected in the circuit of the pair of contacts and bent at its apex to co-operate with the detent and release the movable member on the strip becoming heated.
2. A circuit breaker for an electric circuit

comprising a pair of contacts, a pivotally mounted member of insulating material carrying a conducting stud and movable between said contacts to bring the stud into engagement with the contacts and to move it from the contacts, spring means to move the member, a spring arm mounted at one end on the pivot and carrying a pin at the other end which engages the member of insulating material, a movable arm, a stop mounted thereon and engaging the pin, a V-shaped bi-metallic strip member electrically connected in the circuit of the pair of contacts with its base bent over to embrace the end of the spring arm, and which on the strip being heated will engage the spring arm and remove the pin from engagement with the stop.

Dated this 2nd day of September, 1926.

MARK STAVELEY HOBAN.
